UNITED STATES PATENT OFFICE.

EDWARD STANISLAUS LOUIS, OF LONDON, ENGLAND.

CAKE STAND AND LIKE PORTABLE STAND.

Application filed February 25, 1925, Serial No. 11,601, and in Great Britain March 10, 1924.

The invention relates to cake stands and like portable stands comprising a plurality of trays or similar holders arranged one above the other at intervals in the height of 5 an upright supporting frame, at the upper end of which a handle is provided by means of which the stand may be carried.

The invention is concerned with portable stands of the collapsible type in which means 10 are provided to lock the stand, when desired, against collapsing movement, and in which the supporting uprights for the trays comprise links which are pivotally connected to the trays in such manner as to constitute 15 therewith a parallel-motion linkage. With an arrangement of this kind the trays have a parallel motion in relation to one another when the links are moved to collapse or to erect the stand.

20 The object of this invention is to provide an improved stand of the above type which may readily be collapsed or erected by swinging (by means of the handle aforesaid) the supporting links about the base of the stand, the trays being maintained horizontal 25 during this operation.

The present invention provides a portable collapsible stand of the type referred to above, wherein the base of the stand is constituted by the lowermost tray, the supporting links terminating at their lower ends in 30 pivotal connections with the edges of said tray, so that the stand may be collapsed or erected as aforesaid by swinging the supporting links about their lower ends.

The invention further provides a stand of the aforementioned type, characterized in that the supporting linkage for the trays includes two links located at opposite ends 40 (or sides) of the trays and pivotally connected thereto at points which are spaced apart from the centres of said ends (or sides) on that side towards which the trays are moved when the stand is erected, and the two links aforesaid are connected by a handle. The advantage of this construction will hereinafter be referred to. Where this construction is employed the supporting links may, if desired, be extended beyond 45 the lowermost tray provided the extreme ends of the links which are to rest on the floor or ground are located on straight lines which pass through the pivotal connections of the links to the trays.

55 Some embodiments of the invention will

now be described with reference to the accompanying drawings in which—

Figure 1 is a perspective view of the stand in its erect position.

Figure 2 is a similar view showing the 60 stand partially collapsed.

Figure 3 is an end elevation of the stand completely collapsed.

Figure 4 is an end elevation of the stand in the erect position and showing a modified 65 form of locking device.

Figure 5 is an end elevation of the stand according to Figure 4 in the collapsed position, and

Figure 6 is a perspective view of the stand 70 showing a modified form of supporting links.

Like reference numerals indicate like parts in the various figures.

The stand comprises two shallow trays, 75 10, 11, of rectangular form adapted to be supported one above the other. The lower tray 11 constitutes the base of the stand and the upper tray 10 is supported therefrom in the following manner. Two pairs of parallel links 12, 13, are pivotally connected to the lower tray, one pair at each end thereof. When the stand is erect the two links at each end of the base extend vertically upwards therefrom and the two members of 80 each pair are spaced apart in the vertical end plane containing them. The top tray 10 is pivotally connected at each end to the links 12, 13 aforesaid near the upper ends thereof, the points of connection being such 85 that the top tray is parallel with the base 11. Corresponding links 12 at opposite ends of the stand are extended upwardly beyond the top tray and the two extended portions 14 are coupled together by a cross-piece 15 90 95 which provides a handle for the stand. The extended end portions 14 are curved so that the cross-piece 15 lies directly over the centre line of the upper tray, that is directly over the centre of gravity of the stand as a 100 whole when the latter is erect.

In the construction shown in Figures 1-3 the stand is locked in the erect position by means of two pairs of knuckle-jointed straps 16 pivotally connected between the extended 105 portions 14 of the links 12, and the upper ends of the short links 13. When the stand is to be collapsed the straps 16 are moved out of line and the handle 15 is swung down into the horizontal position.

It will be seen that the trays 10, 11 together with the parallel links 12, 13 supporting them constitute a parallel motion linkage and that as the links are collapsed about the base of the stand the upper tray 10 moves parallel to itself and therefore remains at all times horizontal. The spacing between the two links of each pair and the interval between the trays is such that when the stand is collapsed the trays are brought into a substantially horizontal position alongside each other. When the stand is collapsed as shown in Figure 3 the two links of each pair are brought into contact one above the other and the two trays lie substantially in the same horizontal plane and constitute a single flat tray. If desired means (not shown) may be provided to lock the stand in this position so that when collapsed it may be used as a single tray.

In a modified construction, illustrated in Figure 6, the stand is provided with crossing links 17 hinged at 22 to the side edges of the upper and lower trays. The object of the links 17 is to increase the endwise rigidity of the stand when the latter is in the erect position. In the construction illustrated the links 17 are substituted for the short links 13, but it will be understood that the links 17 may be provided in addition to the links 12, 13. It is not necessary that the links 17 should be arranged to cross each other as shown; rigidity in an endwise direction can be secured by other arrangements provided the side links lie astant the edges of the trays to which they are connected.

In the arrangement shown in Figures 4 and 5 each pair of knuckle-jointed straps 16 in the fore-going example is replaced by a single slotted bar 18. The bars 18 are pivotally connected at one end to the upper ends of the short links 13 and the slots 19 in the bars are engaged by pins 20 on the long links 12 of the stand. Assuming the stand to be in the collapsed position as shown in Figure 5 it will be seen that when the handle 15 is raised the pins 20 will ride up the slots 19 until they reach the extremities of the slots which are formed with enlargements 21 to engage the pins 20 and lock the stand in the erect position. The bars 18 are curved so that when the stand is in the collapsed position as shown in Figure 5 the bars 19 and the supporting links 12, 13, lie substantially horizontal at the edges of the trays.

It is a feature of the examples described herein that the links 12 to which the handle 15 of the stand is attached are connected to the ends of the trays at points spaced apart from the centres of said ends on that side towards which the upper tray is moved when the stand is erected. In the event of uneven loading of the trays, where say a

load on the tray 10 has been placed principally on that side which is next the adjacent tray 11, the above disposition of the links 12 overcomes any tendency of the trays to foul one another at their adjacent edges when the handle is raised to erect the stand.

An advantage of this invention is that the trays may be filled when the stand is in the collapsed position, the parallel motion linkage ensuring that the trays remain horizontal while the stand is being erected. A further advantage is that the stand when collapsed is in a compact form which facilitates packing for transit. Obviously there may be any convenient number of trays or similar holders provided by the stand. If desired the supporting links may be extended beyond the lower tray in order to furnish legs for the stand. With this construction the lower ends of these legs constitute the aforesaid base about which swinging movement of the links takes place. The base of the stand may be furnished with castors or wheels so that when in the erect position it can be readily wheeled about from place to place.

I am aware that in connection with display devices it has hitherto been proposed to employ a plurality of shelves or the like interconnected by parallel links in such manner that by swinging movement of the links the shelves may be brought from a position one above another into a position in which they lie edge to edge alongside one another and constitute a single substantially flat shelf or table. In display devices of the above kind the unit comprising the shelves and their interconnecting links is itself mounted on a supporting stand. I make no claim to any device of this nature.

What I claim as my invention and desire to secure by Letters Patent is:

1. A portable collapsible stand comprising in combination a rectangular tray arranged to rest on the ground and to constitute the base of the stand, parallel vertical links arranged in pairs at opposite ends of the tray aforesaid, with the members of each pair spaced apart in the end plane containing them and pivotally connected at their lower ends to the marginal portions of the tray in such manner as to permit of swinging movement of the links in the aforesaid end plane, a second tray similar to the bottom tray and supported by the upper ends of the links aforesaid in a horizontal position directly above the bottom tray, the links being pivotally connected to the upper tray in like manner to their connection with the lower tray and the spacing between the two trays being approximately equal to the width of each tray, extension pieces forming upward continuation of corresponding links at opposite ends of the stand, said extension pieces being curved in such manner that their extremities

lie over the centre line of the upper tray, a cross-piece interconnecting the extremities aforesaid, and two pairs of knuckle-jointed straps operatively connected between said extension pieces and the upper ends of the adjacent unextended links.

2. A portable collapsible stand comprising in combination a plurality of horizontal trays which, in the erect position of the stand, are spaced apart one vertically above another, a plurality of vertically-extending links interconnected pivotally with the marginal portions of the trays at opposite ends of the stand in such manner that all of the links aforesaid may be swung in parallel about their lower ends as pivots from a vertical position into a substantially horizontal one and vice versa, but at the same time effecting relative parallel movement of the trays from positions one above another into positions alongside each other and vice versa, extension pieces forming upward continuations beyond the uppermost tray of corresponding links at opposite ends of the stand, a cross-piece interconnecting the extension pieces aforesaid and constituting a handle by means of which the stand may be carried, collapsed, and erected, and means operable at will to lock the stand in its erect position.
3. A portable collapsible stand of the type described comprising in combination a plurality of similar trays which, in the erect position of the stand, are located horizontally one above the other at spaced intervals, with the lowermost tray resting on the ground and forming the base of the stand, a plurality of vertically extending links inter-

connected pivotally with the marginal portions of the trays in such manner that all of the links aforesaid may be swung in parallel about their pivotal connections with the lowermost tray from a vertical position into a substantially horizontal one and vice versa, at the same time effecting relative parallel movement of the trays from positions one above another into positions alongside each other and vice versa, a handle located above the uppermost tray and connected to certain of the links in such manner that the handle may be used for swinging the links as aforesaid about their lower ends, and means operable at will to lock the stand in its erect position.

4. In a portable collapsible stand of the type described the combination of a plurality of trays which, in the erect position of the stand, are located horizontally one above the other at spaced intervals, a plurality of parallel links all of which are pivotally connected to each tray and are movable in parallel about their lower ends as pivots from a vertical position into a substantially horizontal one and vice versa, the trays being lowered by said movement from positions one above another into positions alongside each other and vice versa, means operable at will to lock the stand in its erect position, and a handle attached to certain of the links aforesaid for carrying the stand and for swinging the links as aforesaid about their lower ends.

In testimony whereof I affix my signature.

EDWARD STANISLAUS LOUIS.
